OWEN BROOKE EVANS, OF LANSDOWNE, PENNSYLVANIA, ASSIGNEE TO THE UNITED GAS IMPROVEMENT COMPANY, OF PHILADELPHIA, PENNSYLVANIA, A CORPORATION OF PENNSYLVANIA.

PROCESS OF BURNING SOLID FUEL.

1,073,668.

Specification of Letters Patent. Patented Sept. 23, 1913.

Application filed March 26, 1912. Serial No. 686,234.

To all whom it may concern:

Be it known that I, OWEN BROOKE EVANS, a citizen of the United States, residing at Lansdowne, in the county of Delaware and 5 State of Pennsylvania, have invented a new and useful Process of Burning Solid Fuel, of which the following is a specification.

The present invention is applicable to gas producers, the combustion therein being incomplete and the gas generated conducted therefrom and used separately, and it is also applicable where the combustion within the device is complete.

The principal object of the present invention is to prevent or minimize the agglomeration in the form of so-called clinker of the partly melted residuum of the forced combustion of a bed of coal or fuel which has a fusible ash.

20 To this and other ends hereinafter set forth the invention, generally stated, consists in maintaining in the fuel bed superposed zones of relatively high and low temperatures such as will and will not melt and 25 agglutinate the residuum or ash into clinker by apportioning a divided blast between them; feeding through the upper and hotter zone a sufficient quantity of unburned fuel along with the residuum or ash of the burned 30 fuel for preventing agglomeration of the partly melted ash or residuum into clinker, and feeding the last mentioned unburned fuel and divided residuum to the lower and cooler zone and there burning such fuel at a 35 temperature insufficient to agglutinate the divided residuum.

The process of the invention will be claimed at the end hereof and can be practised by means of a great variety of apparatus and alone or in connection with other industrial processes. However, it will be described in connection with the accompanying drawings in which—

Figure 1, is a vertical section of one type 45 of gas producer or generator. Fig. 2, is a similar view of another type. Fig. 2^A, is a transverse sectional view of Fig. 2, and Fig. 2, is a vertical section of a third type of producer or generator.

50 Referring to the drawings the bed of fuel is shown as contained in a generator 1, having a fuel intake 2, and an off-take 3, for products of combustion, fuel gas or the like, and 5, are superposed zones of relatively

high and low temperatures. These zones 55 need not be sharply defined although they in fact exist. As shown in Fig. 1, the zones may be said to be confluent. As shown in Fig. 2, they are partly separated by the bridge wall 6, and as shown in Fig. 3, they 60 are separated by the grate 7, which may of course be water cooled. These zones 4 and 5, of relatively high and low temperatures are maintained by apportioning a divided 65 blast between them. In Fig. 1, the divisions of the blast are applied to the different zones by pipes or connections 8 and 9, one terminating beneath and the other above the grate 10. This is accomplished in Fig. 2, by the pipes or connections 11 and 12. The 70 connection 11, discharges beneath the grate 10, and the connections 12, discharge beneath the bridge 6, which distributes the blast by reason of the space 13, beneath it. In Fig. 3, the connection 14, supplies the 75 blast beneath the grate 10, and the connection 15, supplies the blast beneath the grate 7.

The blast referred to is primarily intended to be an air blast such as is used in forced combustion or gas making but it is not intended to exclude the use of steam. For the sake of further description and without intending to limit the claims, it may be said that with anthracite coal the maximum temperature of the zone 4, might be, for example, 3,000° F. and the maximum temperature of the zone 5, 2,000° F. both more or less. The total blast may be apportioned 85 75% thereof to the zone 4, and 25% thereof 90 to the zone 5, both more or less. The temperature in the part of the fuel bed, for convenience referred to as the zone 4, is sufficiently high to cause melting and agglomeration of the residuum of the combustion 95 of fuel which has a fusible ash into masses usually called clinkers, and the temperature in the part of the fuel bed, for convenience referred to as the zone 5, is lower and is not sufficiently high to cause 100 such agglomeration but in the zone 4, there is present sufficient carbon for preventing 105 agglomeration into clinker of the fused or partially fused residuum, and the presence of this fuel in the zone 4, is insured by proper feeding. The fuel last referred to descends to and is consumed in the zone 5, where the temperature is so low that ag-

- glutination into clinker of the divided residuum does not take place. For the sake of further description but without intending to limit the claims, it may be said that at the 5 top of the fuel bed there is fuel and at the bottom there is a divided residuum of combustion free or at any rate substantially free from clinker, and that at the zone 4, there is present sufficient carbon for preventing agglutination of the fused or partly fused residuum, so that what is known as clinker is practically absent. As an illustration and not to limit the claims, it may be said that in the zone 4, and in the case of 10 anthracite coal, there is present about one-half carbon and one-half residuum. Incidentally it may be remarked that for economic and other well known reasons it is necessary in the combustion of fuel which 15 has a fusible ash to raise the temperature to a point at which such ash would, if unrestrained and uncontrolled, agglutinate into masses called clinkers. By the present invention, however, the existence of these high 20 temperatures, which are high enough to fuse the residuum, is limited to that portion of the fuel bed which has sufficient carbon to prevent the fused residuum from agglutinating and in that way clinkers are avoided 25 while at the same time combustion of the fuel is satisfactorily carried on under forced draft. It is hardly necessary to state that to remove clinkers is a laborious operation 30 and the presence of clinkers interferes with combustion so that the importance of avoiding the formation of clinkers is for these 35 reasons, as well as for many other reasons well known to those skilled in the art, obvious. Even if the temperature in the zone 40 4, is sufficient to fuse or melt the ash there is carbon left in the material which carbon works into the lower zone and is there burned because such carbon moves down through the zone 4, to take the place of the 45 carbon burned in the zone 5, or by reason of the removal of ash from the zone 5. It might be said that even if the conditions are
- favorable in the zone 4, for burning carbon, still the feed through that zone is so fast that all of the carbon in that zone is not 50 burned.
- What I claim is:
1. In the forced combustion of a bed of fuel having a fusible ash, the improved process of preventing clinker which consists 55 in maintaining in the bed superposed horizontal zones of relatively high and low temperatures such as would and would not melt and agglutinate the residuum of combustion by apportioning a divided blast between the 60 zones, uniting the divided portions of the blast and conducting the same through the upper zone and superposed fuel, feeding through the upper and hotter zone sufficient fuel for insuring the presence of enough 65 carbon mixed with residuum for preventing agglutination of the partly melted residuum, and feeding the last mentioned fuel and divided residuum to the lower and cooler zone and there burning the fuel at a 70 temperature insufficient to agglutinate the residuum.
  2. The process of preventing the formation of clinkers in the combustion of a bed of fuel having a fusible ash, which consists 75 in maintaining in the bed superposed horizontal zones extending all the way across the bed each of uniform temperature throughout its extent and whereof one zone is of relatively high temperature and the other is of 80 relatively low temperature, preventing the agglutination of the fused residuum in the first mentioned zone by maintaining carbon admixed with the residuum, and thereafter burning the last mentioned carbon out of 85 the divided residuum in the last mentioned zone at a temperature insufficient for agglutinating such divided residuum.
- In testimony whereof I have hereunto signed my name.

OWEN BROOKE EVANS.
